UNITED STATES PATENT OFFICE.

CHARLES W. CROCKETT, OF LAHAINA, TERRITORY OF HAWAII.

MATCH-BOX HOLDER.

1,200,441.

Specification of Letters Patent.

Patented Oct. 3, 1916.

Application filed May 3, 1916. Serial No. 95,179.

To all whom it may concern:

Be it known that I, CHARLES W. CROCKETT, a citizen of the United States, residing at Lahaina, in the county of Maui, Territory of Hawaii, have invented certain new and useful Improvements in Match-Box Holders; and I do hereby declare the following to be a full, clear, and exact description of the invention, such as will enable others skilled in the art to which it appertains to make and use the same.

The present invention is directed to improvements in holders for match boxes, and particularly that type of box which contains safety matches and is carried on the person.

The invention has for its object to provide a holder of this character constructed in such a manner as to hold the box portion positively against accidental loss or removal from a cover.

A further object of the invention is to provide a holder having associated therewith a spring which serves to retain the box portion normally and wholly enveloped by the cover, but at the same time permitting the box portion to be partially slid from the cover and returned by the spring after a match has been removed.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a perspective view of the holder showing a match box contained therein; Fig. 2 is a top plan view of the holder, the holding plate being shown in its inoperative position; Fig. 3 is a transverse sectional view through the holder; and Fig. 4 is a longitudinally sectional view therethrough.

The holder consists of a base plate 1, which has its longitudinal edges terminating in vertical flanges 2, while its end edges are rolled to provide sleeves 3 which are engaged by the bars 4 said bars serving to support the side frames 5. To one of the horizontal bars 6 of one of said frames is hingedly connected one end of a holding

plate 7, the other end of which is adapted to be engaged under the bar 6 of the other frame, thus holding the plate in its operative position and engaged with the cover of the match box 8. Bowed springs 9 are secured to the base plate 1 and adjacent its side edges and serve to yieldably hold the box in contact with the plate 7.

Since the frames 5 are formed from resilient wire it is obvious that the same can be spread apart sufficiently to permit the free edge of the plate 7 to engage under the adjacent bar 6.

A zig-zag spring 10 is mounted on the plate 1 and has its central portion fixed thereto in any suitable manner. Each outer bar 11 of the spring has one end terminating in an integral hook 12, while the other ends of said bars have suitably connected thereto similarly shaped hooks 13. These hooks are adapted to have their bills engage the ends of the box portion 14.

From the foregoing description it will be seen that a match box can be easily placed in the holder and the box portion slid in either direction, said box portion being returned to its normal or closed position by the spring 10.

What is claimed is:—

1. A match box holder comprising a base plate, a spring carried by the base plate and having hooks at its ends for engaging the ends of the box portion to hold the same within the cover and means for holding the box on the plate.

2. A match box holder comprising a base plate, side frames carried by the plate, a spring associated with the base and having hooks on its ends, a holding plate pivotally connected to one side frame and having its free end engaged with the other side frame to engage the cover of the match box, the box portion of which has its ends engaged by said hooks.

3. A match box holder comprising a base plate, a spring carried by the plate and having means at its ends for yieldably engaging the ends of the box portion.

In testimony whereof, I affix my signature, in the presence of two witnesses.

CHARLES W. CROCKETT.
